BARNET S. MINTERS, OF GREAT NECK, NEW YORK

AUTOMATIC CONTROL DEVICE

Application filed May 20, 1931. Serial No. 538,781.

This invention relates to automatic control devices for gas ovens.

Among the objects of this invention is to provide in a gas range or the like, a neat, rugged, compact and practical control device of the character described, comprising few and simple parts, substantially concealed between the outer walls and lining of the oven, which shall be comparatively inexpensive to manufacture, positive and smooth in operation and practical and efficient to a high degree in use.

Other objects of this invention will in part be obvious and in part hereinafter pointed out.

The invention accordingly consists in the features of construction, combinations of elements, and arrangement of parts which will be exemplified in the construction herein-after described, and of which the scope of application will be indicated in the following claims.

In the accompanying drawings, in which is shown one of the various possible illustrative embodiments of this invention,

Fig. 1 is a front elevational view of a portion of a gas range provided with control means embodying the invention, with parts broken away to show the interior of the construction;

Fig. 2 is a top plan view of the structure shown in Fig. 1, with parts broken away to show the interior of the construction;

Fig. 3 is a cross-sectional enlarged detailed view of the gas valve forming part of my improved device;

Fig. 4 is a cross-sectional view taken on line 4-4 of Fig. 2; and

Fig. 5 is a front elevational enlarged detailed view of a portion of the device shown in Fig. 1.

Referring now in detail to the drawings, 10 designates a portion of a gas range provided with the usual cooking oven 11, broiling oven 12 and a substantially rectangular shaped gas burner 13 interposed between said ovens. The gas may be fed to the burner 13 by means of a gas supply pipe 15, which also supplies gas to the usual open burners (not shown) in the well known manner.

The pipe 15 may be connected to said burner 13 by means of a pair of nipples 16 and 17, a gas valve 18 interposed between said nipples, and a pipe 19 connected to the nipple 17 by means of an air inlet valve 20. 55

The valve 18 may be of ordinary construction and preferably comprises a housing 22 having an internal partition formed with a central tapered valve opening 24. Said opening may be closed by a valve closure member 25 formed at one end of a stem 26 slidably extending through a bore in said housing. The stem 26 is provided with a head 28 at the other end thereof, and a coiled compression spring 29 is interposed between said head 28 60 and the housing. The valve is thus normally retained in closed position, and may be opened upon pressure being exerted against the head 28.

Means is provided for opening the gas 70 valve a predetermined amount depending upon the desired temperature in the ovens 11, 12, and for thermostatically retaining said valve in said regulated position, whereby an even predetermined temperature may 75 be maintained within the oven. To this end there is mounted between the vertical lining 32 of the oven and the outer wall 33 thereof, a vertical tubular member 34 closed at the upper end thereof by a plug 36 or in any other 80 suitable manner. Screwed to said tubular member 34 adjacent the upper end thereof is a horizontal elongated tubular member 37 made of copper or the like material having a relatively large co-efficient of expansion, 85

said copper tube extending through said lining wall 32 and projecting into the oven 11 adjacent the top thereof. The outer end of the tube 37 may be closed by an adjustable cap 38, preferably screwed to the said outer 90 end thereof. Pivoted to said member 34 medially the ends thereof, as for example, on a horizontal pivot 39 is a lever 40. Attached to the upper end 41 of said lever 40 is a member 42 having a flat surface for the purpose 95 herein-after described. Slidably mounted within said tubular member 37 and spaced therefrom as for example by means of a plurality of spaced ring members 43 is an elongated rod 44 made of porcelain or the like 100.

material having a relatively small co-efficient of expansion, said rod being attached at the outer end 44a thereof, to said cap 38 in any suitable manner, for example, by means of a 5 ring 38a concentrically formed with said cap and receiving said end of said rod therein. The inner end 46 of the rod 44 is preferably formed with a knife edge contacting said flat surface of member 42. The lower end of the 10 lever 40 has a portion 49 bent substantially at right angles thereto, and extending downwardly from said portion 49 is an arm 50 bent inwardly as at 51. Pivoted to said inwardly bent portion 51 is a vertical floating lever 52 15 having an end portion 53 contacting the head 28 of the gas valve 18.

It will now be clear that a pull to the left on the lower end 54 of the floating lever 52 will cause the upper end 53 thereof to press 20 said head 28 and compress the spring 29 for opening the valve. For causing pivotal movement of the floating lever there is rotatably mounted on the front wall 56 of the gas range to the left of the oven portion thereof, 25 a horizontal shaft 57 to the front end whereof is attached a handle 59 having a pointer 60. Attached to the front surface of said wall 56 is a dial 61 bearing "Off" and "On" 30 marks and temperature indicia for cooperation with the pointer 60. Attached to the inner end of said rod 57 is a disc or wheel 63 having ratchet teeth 64 at the periphery thereof. A spring 65 fixed as at 66 to a horizontal floor or wall portion 70 of the gas 35 range, is provided with an end portion 67 adapted to engage said teeth 64 for retaining the disc in any position to which it may be moved. Eccentrically fixed to said disc is a pin 68 projecting rearwardly therefrom. 40 Slidably mounted on said floor portion 70, is a member 71 having a horizontal portion 72 retained on said wall 70 by means of a pair of spaced guide straps 73. Extending upwardly from one end of said portion 72 is a 45 bifurcated arm 74 having a slot 75 slidably receiving said pin 68 therein. Extending upwardly from the opposite end portion 72 is an arm 76 adapted to contact the lower end 54 of said floating lever 52.

50 The operation of the device will now be clear. In normal position with the pointer 60 pointing to the "Off" mark on the dial 61, the arm 76 is in the dotted position shown in Fig. 5, and the spring 29 is permitted to 55 push the stem 26 to the left for closing the valve 18. Upon turning the handle 59 however, the pointer 60 may be brought to any desired point on the dial 61, for example to the point marked 350°. This movement of 60 the handle will cause the disc 63 to be rotated for slidably moving the member 72 to the left and causing the floating lever to be pivoted about portion 51 and press the valve against the compression spring 29, into open position. 65 The burner obviously lights automati-

cally by means of any suitable pilot upon opening of the valve 18, as is well known in the art. During this movement, the lever 40 does not rotate about the pivot member 59 since the upper end thereof contacts rod 44 which in turn is fixed at the outer end thereof to cap 38. Said lever thus remains stationary during setting movement of the valve. However, should the oven rise to a temperature greater than 350° the copper tube 37 will 70 expand and the cap 38 will move to the right, thus pulling rod 44 therewith. The compression spring 29 will then rotate lever 52 about end portion 54 thereof in a counter-clockwise direction. This movement will 75 cause the lever 40 to rotate about pivot 39 in a clockwise direction, such rotation being permitted by movement of the rod 44. The valve stem 26 thus moves to the left under the influence of the compression spring 29 toward closing position. The spring 29 serves to retain the upper end of lever 40 in contact with end 46 of rod 44.

The gas supply to the burner 13 will hence be diminished to decrease the temperature 80 within the oven.

Upon decrease of the temperature within the oven, the copper tube 37 will contract and cause the rod 44 to be pushed to the left, thus causing the lever 40 to pivot in a counterclockwise direction for pivotally moving the floating lever 53 about the lower end 54 in a clockwise direction. The valve stem is thus moved to the right for again opening the same to increase the flow of gas to the burner 13. 100

It will be noted that the handle 59 remains in any position to which it is set by reason of the engagement of spring 65 with the teeth 64 of the disc 63. The temperature within the oven will thus remain constant since, if it is increased beyond the predetermined point the temperature will be lowered and if it is moved below the predetermined point, the temperature will be automatically increased. 105

A usual gas range stop cock valve 57a may be interposed in the supply pipe or manifold 15, the shaft 57 being adapted to actuate said valve. The valve 57a serves as a safety closure valve and also serves to limit the maximum gas supply to the burner 13. 110

The valve 18 may be attached to the tubular member 34 in any suitable manner whereby the relative positions of the copper tube 37, rod 44, levers 40 and 52 and valve 18 are 115 fixed to ensure proper operation of the control mechanism. Further with this construction, said mechanism may be installed as a unit, either in new gas ranges or in ranges now in use. 120

It will thus be seen that there is provided a device in which the several objects of this invention are achieved, and which is well adapted to meet the conditions of practical use. 125

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. In a gas oven having a cooking chamber, a gas burner within said chamber, means for supplying gas to said burner, a gas valve interposed in said supply, said valve including a movable valve member and a spring normally urging said member to closing position, and means for controlling said valve, said means comprising a tubular member made of material having a relatively high coefficient of expansion attached at one end thereof to a portion of said oven, and extending into said chamber, a lever pivoted to said oven, a member made of material having a relatively small co-efficient of expansion within said tubular member and contacting the free end of said tubular member at one end thereof, and one end of said lever at the opposite end thereof, a floating lever pivoted mediate the ends thereof to the opposite end of said first lever, one end of said floating lever being adapted to contact said spring pressed movable valve member, and manually actuated means engaging the opposite end of said floating lever for rotating the same about the pivotal point thereof.
2. In a gas oven having a cooking chamber, a gas burner within said chamber, means for supplying gas to said burner, a gas valve interposed in said supply, said valve including a movable valve member and a spring normally urging said member to closing position, and means for controlling said valve, said means comprising a tubular member made of material having a relatively high coefficient of expansion attached to a portion of said oven at one end thereof and extending into said chamber, a lever pivoted to said oven, a member made of material having a relatively small co-efficient of expansion within said tubular member, contacting the free end of said tubular member at one end thereof, and one end of said lever at the opposite end thereof, a floating lever pivoted mediate the ends thereof to the opposite end of said first lever, one end of said floating lever being adapted to contact said spring pressed valve member, and manually actuated means engaging the opposite end of said floating lever for rotating the same about the pivotal point thereof, said manually actuated means comprising a handle, a disc attached to said handle and adapted to be rotated therewith, a member interconnecting said disc with said floating lever, and resilient means for retaining said disc against accidental movement.

3. In combination with an oven, a gas burner therein, a gas valve for controlling the supply of gas to said burner, said valve including a spring pressed closure member, a lever pivoted mediate the ends thereof to said oven, a floating lever pivoted to one end of said first lever and adapted to contact said closure member, thermostatic means extending into said oven operatively connected with the other end of said first lever, for automatically controlling said closure member, and manually actuated means for rotating said floating lever about the pivotal point thereof for initially setting said closure member.

4. In combination with an oven, a gas burner therein, a gas valve for controlling the supply of gas to said burner, said valve including a spring pressed closure member, a lever pivoted mediate the ends thereof to said oven, a floating lever pivoted to one end of said first lever and adapted to contact said closure member, thermostatic means extending into said oven operatively associated with the other end of said first lever for automatically controlling said closure member, manually actuated means for rotating said floating lever about the pivotal point thereof, and means for retaining said manually actuated means in any position to which the same may be moved.

5. Valve control means comprising a movable closure member, an elongated member made of material having a relatively high coefficient of expansion fixed at one end thereof, a lever pivoted to a fixed pivot mediate the ends thereof, a member having a relatively small co-efficient of expansion interposed between one end of said lever and the opposite end of said elongated member, a second lever pivoted mediate the ends thereof to the opposite end of said first lever, said second lever having an arm contacting said closure member, and manually actuated means adapted to engage the other arm of said second lever for causing rotation of said second lever.

6. Valve control means comprising a movable spring pressed closure member, an elongated member made of material having a relatively high co-efficient of expansion fixed at one end thereof, a lever pivoted to a fixed pivot mediate the ends thereof, a member having a relatively small co-efficient of expansion interposed between one end of said lever, and the opposite end of said elongated member, a second lever pivoted mediate the ends thereof to the opposite end of said first lever, and having an arm contacting said closure member, adjustable means adapted to engage the other arm of said second lever for causing rotation of said second lever, and means for retaining said adjustable means in any position to which the same may be adjusted.

7. In combination with a cooking oven, a gas burner therein, means for supplying gas to said burner, a gas valve interposed within said supply means, including a closure member and a spring adapted to move said closure member to closing position, means for controlling said valve, comprising a tubular member made of material having a relatively high co-efficient of expansion attached at one end thereof to a portion of said oven and extending into said oven, a lever pivoted mediate the ends thereof to said oven, an elongated rod having a relatively small co-efficient of expansion within said tubular member having one end thereof fixed to the free end of said tubular member and the other end thereof contacting one end of said lever, a second lever pivoted at the opposite end of said first lever and having one end contacting said closure member, adjustable means for engaging the opposite end of said second lever for rotating the same to press said closure member against said spring toward opening position, and means for releasably retaining said last mentioned means in adjusted position.

8. Valve control means for a burner comprising an elongated member made of material having a relatively high co-efficient of expansion and fixed at one end thereof, and adapted to extend into a heating chamber, a pivoted lever, a member made of material having a relatively low co-efficient of expansion interposed between a portion of said first member and a portion of said lever, a floating lever pivoted to said first lever, one end of said floating lever being adapted to actuate said valve, and movable means engaging said floating lever for rotating the same about the pivotal point thereof.

40 In testimony whereof I affix my signature.
BARNET S. MINTERS.
